DRIFT TUBE FOR KLYSTRON

Clayton E. Murdock, Millbrae, Calif., assignor to Eitel-McCullough, Inc., San Bruno, Calif., a corporation of California

Application July 20, 1954, Serial No. 444,426

3 Claims. (Cl. 333—83)

My invention relates to klystrons having cavity resonators, and more particularly to such klystrons in which the resonators have portions forming part of the evacuated envelope and separated from external resonator portions by vacuum-tight insulating walls.

It is among the objects of my invention to provide a klystron of the character described which is made up of a series of structural units or subassemblies separately fabricated and later joined at seals spaced along the axis of the envelope.

Another object is to provide improvements in the resonator structures which form part of the evacuated envelope.

Another object is to provide an improved joint structure between resonator end walls and a ceramic cylinder which comprises the insulating wall member.

Still another object is to provide such a structure where-in the final seals are made at the above mentioned joints after the subassemblies have been completed.

A further object is to provide an improved method of assembling the klystron.

The invention possesses other objects and features of advantage, some of which, with the foregoing, will be set forth in the following description of my invention. It is to be understood that I do not limit myself to this disclosure of species of my invention, as I may adopt variant embodiments thereof within the scope of the claims.

Referring to the drawing:

Figure 1 is an axial sectional view of a three-cavity klystron embodying my invention; and

Figure 2 is an exploded view showing the subassemblies prior to making the final seals.

In its preferred form as illustrated in Figure 1, my improved klystron comprises an elongated generally cylindrical evacuated envelope having an electron gun assembly 2 at one end and a collector electrode assembly 3 at the other end. The electron beam from the gun to the collector passes through a drift tube made up of sections 4, 6, 7, and 8 of a metal such as copper extending axially of the envelope and having gaps 9 therebetween. The gaps are bridged by cavity resonators generally designated at 11.

Electron gun 2 comprises a cathode 12 housed in a cup-shaped anode 13, say of copper. The anode is fixed to drift tube section 4 at braze 14 and has an aperture 15 ahead of the cathode and opening into the drift tube. Electrons from the cathode are focused through the anode aperture by a focusing electrode 16. The entire gun structure is mounted on a suitable stem 17 at the end of the envelope, which stem may be of conventional glass and metal construction and providing suitable terminals for the cathode.

The gun structure of my improved klystron comprises a unitary subassembly which may be separately fabricated as shown in Figure 2. Gun assembly 2 is sealed to anode 13 at a joint comprising a pair of nested metal flanges 18 and 19 on the stem and anode respectively, flange 18 being sealed to a glass wall of the stem and flange 19

2

being brazed at 20 to the end of anode 13. These ring-shaped flanges are concentric with the envelope axis and when fitted together are welded along the registering edges at 21 to provide a vacuum-tight seal at this joint.

Collector assembly 3 at the opposite end of the envelope comprises a cup-shaped collector electrode 22, say of copper, connected to drift tube section 8 at braze 24. Collector electrode 22 also preferably carries a metal exhaust tubulation 25 which is pinched off at 26 after evacuation 10 of the envelope. The collector may be cooled by a suitable water jacket 27 or the like.

The collector structure thus also comprises a unitary subassembly which may be separately fabricated as shown in Figure 2. This collector assembly, including the last 15 drift tube section 8, is sealed at a joint structure which comprises part of the third cavity resonator, hereinafter described:

The above elements of the electron tube function in the conventional manner for klystron tubes of this type, namely, the electron beam from cathode 12 is accelerated by a positive potential on anode 13 and passes through the drift tube, past the interaction spaces provided by gaps 9, and finally terminates at collector electrode 22. The three cavity resonators 11 coating with the interaction spaces 25 provided by gaps 9 serve as the frequency determining elements of the device. In the three-cavity klystron illustrated, functioning as an amplifier, the radio-frequency input is fed into the first resonator and the output is taken from the third resonator.

In the particular kind of klystron shown in Figure 1 the cavity resonators 11 have extensions 28 externally of the evacuated envelope to permit external tuning. These extensions, one of which is indicated by dotted lines in Figure 1, may simply comprise split rectangular metal 30 boxes fastened to the resonators 11, which boxes contain suitable sliding end walls for changing the resonant frequency of the resonators. The use of such external resonator construction, which permits tuning over a wide frequency range, is made possible because of the sealed-off 35 nature of resonators 11 which comprise part of the evacuated envelope.

Resonators 11 are mounted on drift tube sections 4, 6, 7, and 8 to bridge gaps 9. It is thus seen that the drift tube sections form side walls of the evacuated envelope 45 axially of the klystron and that the resonator structures provide additional vacuum-tight walls bridging the gaps between the drift tube sections. The resonators are of like construction, each comprising a pair of metal end wall disks 29 connected by a cylindrical insulating wall 31. Walls 29, preferably of copper, are apertured to receive the drift tube sections and are fixed to the latter at brazes 50 30.

The final seals are made at joint structures between the resonator end walls 29 and the interposed insulating 55 cylinders 31 so that the klystron is divided into structural units or subassemblies axially along the envelope, as best shown by the exploded view of Figure 2. Thus anode 13, drift tube section 4, and an end wall 29 can be assembled and brazed together as a unit in a brazing furnace. Likewise, drift tube section 6 with another pair of end walls 29 forms another subassembly, and similarly drift tube section 7 with another pair of end walls forms still another subassembly. In a like manner the collector structure on drift tube section 8, which also carries an end wall 29, makes up a further subassembly.

Each of the insulating walls 31 is also made up as a 60 separate structural unit as seen in Figure 2. Cylinders 31 are preferably of ceramic and have metal flanges 32 at the ends which nest in mating flanges 33 projecting from the end walls 29. Flanges 32 and 33 are of a metal such as copper and are preferably relatively thin. The 65 ceramic used is preferably a type having good mechan-

cal and insulating properties, such as alumina, and is metalized at the ends by any of the conventional metalizing techniques so that flanges 32 can be applied.

I prefer to make flanges 32 cup-shaped so that the inverted portions overlap the flat ends of cylinders 31, which overlapping portions are bonded to the metalized ends of the ceramic at brazes 34. Flanges 33 are simple ring-shaped pieces projecting from the end plates and secured thereto at brazes 35. These flanges 32 and 33 are thus arranged concentric with the envelope axis 37 and when finally fitted together are sealed along the registering edges at 36 to provide vacuum-tight joints. Seals 36 are preferably fused metallic bonds, such as welds. It is thus seen that the subassemblies may be slipped together axially and then sealed by welding the flanges.

End walls 29 are preferably undercut at the joints to provide clearance under flanges 32. In order to take the axial thrust of atmospheric pressure, I leave a narrow spacer ring 38 projecting from the end wall and abutting the end of the cylindrical wall structure. This relieves the sealing flanges from stress after the envelope is evacuated and allows the flanges to be made of relatively thin material which is desirable to give some degree of flexibility at the joints.

The relationship between the several structural units prior to final sealing is clearly shown in Figure 2. Ability to fabricate the envelope in separate subassemblies is important in a klystron of this kind where appreciable length and relatively massive parts are involved. For example, in a power klystron capable of delivering, say, ten kilowatts of C. W. power in the UHF region, the tube is several feet long and weighs fifty pounds or so. With my improved construction, the subassemblies are each relatively small and can be put together and brazed in a furnace of convenient size.

It will be noted that the final sealing flanges are all concentric with the tube axis, so that when the subassemblies are put together they may be rotated about the axis during the final welding operations. Welding of the flanges is done with a heli-arc which involves keeping the arc fixed while rotating the work about an axis.

Another important feature of my construction and method of assembly is that the ceramic wall sections, after application of the end flanges 32, do not have to be subjected to additional brazing furnace temperatures. Additional high temperature heat cycling of the flanged ceramic sections is bad because of weakening of the bonds at the metalized areas. The only thing that the flanged ceramic sections are further subjected to in my structure is the heli-arc welding at the flanges, which is a localized heating operation and does not subject the metalized areas to injury.

Still another feature which facilitates the assembly procedure is that sealing flanges 32 and 33 are concentric with the axis 37 and hence serve as self-jigging devices to insure coaxial alignment of the parts. This is particularly important in a klystron wherein alignment of the drift tube sections must be held to close tolerances to insure optimum performance.

The several advantages come about by reason of the improved structure and method of assembly, namely, by fabricating the envelope in a series of separate structurally integral units coaxially aligned along the envelope axis, which subassemblies are joined together at the engaged flanges 32 and 33 having registering edges lying in parallel planes disposed perpendicular to the envelope axis. This structure allows the coaxial metal flanges to be telescoped together by relative movement of the subassemblies axially of the envelope and permits rotating the engaged subassemblies about the common axis so that the sealing operation can be easily accomplished by welding the registering edges of the rotating flanges.

I claim:

1. In a klystron having a drift tube including a series

of metal sections with gaps therebetween, a plurality of resonators each including a pair of metal end walls and an insulating cylinder therebetween, the several pairs of end walls each being fixed to the drift tube sections at opposite sides of a different one of said gaps so that two walls of adjacent resonators together with an interconnecting drift tube section form a structurally integral unit, the improvement comprising a ring-shaped metal flange fixed to each end wall and being in an overlapping externally concentric relationship with respect to the associated insulating cylinder, a cup-shaped ring-like metal end flange fixed to each insulating cylinder and being in an overlapping externally concentric relationship with respect to the associated insulating cylinder and nesting closely within the associated ring-shaped metal flange supported on the adjacent end wall with the edges of said ring-shaped flange and cup-shaped flange in registration, fused metallic bonds uniting the registering and nested edges of the engaged flanges, and a spacer ring supported on each end wall and axially aligned in cross-section with the length of the associated cylinder wall and mechanically coupled to the associated end of the insulating cylinder.

2. In a klystron having a drift tube including a series of metal sections with gaps therebetween, a plurality of resonators each including a pair of metal end walls and an insulating cylinder therebetween, the several pairs of end walls being fixed to the drift tube sections at opposite sides of a different one of said gaps so that two walls of adjacent resonators together with an interconnecting drift tube section form a structurally integral unit, the improvement comprising a ring-shaped metal flange fixed to each end wall and being in an overlapping externally concentric relationship with respect to the associated insulating cylinder, a cup-shaped ring-like metal end flange fixed to each insulating cylinder and being in an overlapping externally concentric relationship with respect to the associated insulating cylinder and nesting closely within the associated ring-shaped metal flange supported on the adjacent end wall with the edges of said ring-shaped flange and cup-shaped flange in registration, fused metallic bonds uniting the registering and nested edges of the engaged flanges, and a spacer ring supported on each end wall and aligned in cross-section with the length of the associated cylinder wall and mechanically coupled to the associated end of the insulating cylinder.

3. In a klystron having a drift tube including a series of metal sections with gaps therebetween, a plurality of resonators each including a pair of metal end walls and an insulating cylinder therebetween, the several pairs of end walls being fixed to the drift tube sections at opposite sides of a different one of said gaps so that two walls of adjacent resonators together with an interconnecting drift tube section form a structurally integral unit, the improvement comprising a first metal flange fixed to each end wall and being in an overlapping externally concentric relationship with respect to the associated insulating cylinder, a second metal end flange fixed to each insulating cylinder and being in an overlapping externally concentric relationship with respect to the associated insulating cylinder and nesting closely within the associated first metal flange supported on the adjacent end wall with the edges of said first and second metal flanges in registration, fused metallic bonds uniting the registering and nested edges of the engaged flanges, and a spacer supported on each end wall and aligned in cross-section with and mechanically coupled to the associated end of the insulating cylinder.
